(57) CLAIM

The ornamental design for a car audio device, as shown and described.

DESCRIPTION

FIG. 1 is a top, front and right side perspective view of a car audio device showing my new design.

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a sectional view thereof along line 8-8 in FIG. 2;

FIG. 9 is a sectional view thereof along line 9-9 in FIG. 2;

FIG. 10 is a top, front and right side perspective view thereof with a slide cover element of the design in an open position; and,

FIG. 11 is a front view thereof showing the slide cover element of the design in the open position.

The portions of the drawings shown in broken lines are for illustrative purposes only and form no part of the claimed design.
